UNITED STATES PATENT OFFICE

CARL V. POHLSON, OF PAWTUCKET, RHODE ISLAND

COMBUSTIBLE CHEMICAL UNIT

Application filed May 16, 1928. Serial No. 278,258.

This invention relates to a combustible chemical unit and has for its object to provide a combustible container carrying an appropriate quantity of combustible chemical crystals to be applied at a single feeding to a log fire, the container being formed of a free burning material such as dry wood, card board or the like, and the crystals in the container being of a character to produce various colors in the flame while burning whereby when the chemical crystals are released by the burning away of the container, the crystals become distributed by action of the flame over the burning logs to produce the desired coloring effects.

A further object of the invention is to provide a package containing a definite number of these units bound together in bundle form, each different unit having a different colored outer surface whereby collectively the units of the bundle suggest the different colors of the flame when acted upon by the released chemicals.

With these and other objects in view, the invention consists of certain novel features of construction, as will be more fully described, and particularly pointed out in the appended claims.

In the accompanying drawings:

Figure 1 is a perspective view showing a bundle of these combustible chemical units in a box with the lid removed.

Figure 2 shows the bundle removed from the box.

Figure 3 is a perspective view of a single combustible container or bottle.

Figure 4 shows the closure cap removed from the bottle.

Figure 5 shows the bottle or container in section with its cap cemented to one end and filled with the combustible chemical crystals.

Figure 6 is a perspective view illustrating one of the chemical combustible bottles as deposited upon the burning logs in a fire blaze.

It is found to be very interesting in the burning of log fires to reproduce the so-called drift wood blaze, the coppers and salts in which serve to produce different colors in the flames from the burning logs.

Also it is found that when chemicals are prepared which contain salts blue vitriol and other chemicals for artificially producing these so-called drift wood blaze effects that when exposed to the air the salt crystals absorb the moisture causing the whole to lump into mass form, which prevents the same from being nicely and evenly sprinkled or distributed over the burning logs of the fire; and to obviate this difficulty in a simple and effective way, I have provided a container or bottle which may be formed of combustible material such as wood, paper or the like and of a size to contain or carry the proper or appropriate amount of chemical crystals to be applied to the fire at a single feeding. This bottle is preferably elongated and after being filled with the chemical crystals is sealed by cementing a closure member on its open end thus excluding the moisture and keeping the charge dry so that when the bottle or unit is applied to the fire the casing will be first consumed thus releasing the chemicals which when acted upon by the flame will be automatically spread about over the logs to produce the desired coloring effects to the flames; also in practice it is found desirable in marketing these goods to assemble them in package form, each package having a definite number of these bottles secured together in a bundle and deposited in a box for shipment, whereby one bottle may be withdrawn at a time and deposited on the fire to produce the different coloring effects to the fire. Also, each of these bottles or containers is preferably tinted with different colors which when assembled in bundle form collectively suggests the different colors produced by the burning chemicals in each bottle and the following is a detailed description of the present embodiment of my invention and showing one means by which these advantageous results may be accomplished:

With reference to the drawings, 10 designates a combustible bottle which may be formed of any suitable material such as pasteboard or other material which will be readily consumed when subjected to a flame.

In this particular instance, I have shown the bottle as being formed of wood with a

central bore of a size and length to receive an appropriate quantity of chemical crystals to be applied to a log fire at a single feeding for producing the necessary coloring effects to the flame. Into this bore is deposited the proper quantity of combustible chemical crystals 11, which crystals are of a character to produce various colors in a flame upon being burned. After these crystals have been deposited in the bottle, a cap or closure member 12 is secured to the open end of the bottle sealing the same against action of moisture and so preventing the crystals from lumping whereby when one of these units which 15 consists of combustible bottle filled with the combustible chemical crystals is subjected to the action of the flame, the bottle or outer envelope upon being consumed releases the dry chemical crystal contents which when 20 acted upon by the flame are distributed over the burning logs to produce the desired coloring effects to the flame.

These units may be marketed in bundle form, each bundle to contain a definite number of units, as illustrated in Figure 2 and the whole may be bound together by a binder member 13 if desired and deposited in a box 14 for shipment.

In some instances, each bottle in the bundle is tinted a different color so that when assembled the units of the whole suggests the different colors of the flame produced by the burning chemicals which renders the package attractive and stimulates sale of the article.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A combustible chemical unit comprising a sealed moisture-proof bottle formed of combustible material and containing combustible chemical crystals of a character to produce various colors in flame when burned, said bottle being elongated and of a size to contain an appropriate quantity to be applied at a single time to a log fire, whereby when the unit is bodily deposited on the burning logs the bottle is consumed and the crystals are acted upon and distributed by the flames over the burning logs to produce the desired coloring effects.

2. A package comprising a bundle of combustible chemical containing distributor units banded together, each unit being formed of a sealed moisture-proof bottle filled with combustible chemical crystals of a character to produce various colors in the flames when burned, each of said bottles of the bundle being of a size to contain an appropriate quantity to be applied at a single time to a log

fire whereby when the unit is bodily deposited on the burning logs and the bottle is consumed its contents are released and are acted upon by the flames and distributed over the burning logs, the different bottles of the bundle being of different colors to collectively suggest the colors in the flame produced by the chemical crystals.

3. A pyrotechnic novelty comprising a combustible moisture-proof casing sealed to prevent ingress of atmospheric air, and dry chemical crystals therein of a character to produce changing colors when burnt, said crystals being released on the burning of the casing.

In testimony whereof I affix my signature.

CARL V. POHLSON.
